GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

VALVE MECHANISM FOR FLUID PRESSURE TOOLS

Application filed August 23, 1928. Serial No. 301,461.

This invention relates to fluid pressure motors of the reciprocating type, particularly those actuating a free flying piston arranged to have a percussive action. More particularly it relates to automatic valve arrangements for such motors when utilized for hammers and hammer drills.

Among the objects of the invention are to devise an improved type of valve which is positively held in a given position, to so arrange the valve that the pressure or pressures which cause its movement come from the piston chamber and are effected or controlled by the piston, to avoid perforations in the valve, and in general to simplify and to improve fluid pressure tools in the interest of increased efficiency and service.

In order to illustrate the invention, one concrete embodiment thereof is shown in the accompanying drawings in which:

Fig. 1, is a longitudinal sectional view partly broken away;

Fig. 2, is a fragmentary sectional view similar to Fig. 1 showing the piston and valve in a different position; and

Fig. 3, is a detail sectional view substantially on the line 3-3 of Fig. 2.

In the embodiment of the invention, chosen for the purpose of illustration, a fluid pressure hammer drill is disclosed having a cylinder 4 providing a piston chamber in which reciprocates a hammer piston 5 having an extension 5a arranged to impart blows to the shank end of a drill steel 6 which is suitably supported for this purpose in a front head 7 secured to cylinder 4. The cylinder provides a valve chamber for an automatically thrown valve 8 which operates in timed relation with the reciprocations of piston 5 and controls the admission of motive fluid to the opposite ends of the piston chamber to drive the piston.

The particular form of valve herein shown, is tubular and has end areas of equal extent and a substantial centrally disposed

stepped flange providing opposed holding areas 9 and 10 and opposed shift areas 11 and 12, the holding areas being of slightly greater extent than the shift areas. The cylinder provides continuously opened vent ports 11a and 12a of limited size for the shift areas and cross ports 11b and 12b extending from the piston chamber at opposite sides of a main piston controlled exhaust 5b. Motive fluid inlet passages 13 and 14 extend from opposite ends of the valve chamber to the proximate ends of the piston chamber and are controlled by the extreme ends of valve 8. Suitable means are provided for establishing and continuously maintaining communications between the holding areas 9, 10 of the valve and the adjacent inlet passages 13 and 14 for the piston chamber. In the present instance such means take the form of axially directed channels adjacent the outer surface of the valve and preferably formed in partitions provided by the cylinder or casing 4 between the holding areas of the valve and the respective end chambers of the valve. Such channels may be one or more in number. By preference four are provided as shown in Fig. 3, the channels leading from passage 13 to holding area 9 being indicated at 9a (Figs. 1 and 2) and those leading from passage 14 to holding area 10 being indicated at 10a (Figs. 1, 2, and 3).

The operation of the motor is as follows. Motive fluid enters the valve chamber through inlet 15 and its distribution therefrom to the piston chamber is controlled by the position of valve 8. With the parts in the position shown in Fig. 1, piston 5 is on its outward or power stroke, the valve 8 being at its extreme right hand position admitting motive fluid directly into inlet passage 14 which extends to the rear of the piston chamber. The admitted motive fluid is effective through channels 10a against holding area 10 to maintain the valve in the position shown. All

other areas of the valve are open to exhaust with the exception of the equal end areas of the valve which are always subject to the pressure of the live motive fluid. As the piston 5 advances, it cuts off the main exhaust port 5b but a portion of the air ahead of the piston can still escape through passage 12b and valve vent 12a until the passage is closed. On further movement of the piston, passage 10 11b is uncovered admitting motive fluid from the rear piston chamber against shift area 11 of the valve. A portion of such motive fluid passes at once to atmosphere through vent 11a but since vents 11a and 12a are of 15 much smaller capacity than shift passages 11b and 12b, a substantial pressure builds up against area 11. This is insufficient, however, to shift the valve because holding area 10 is of greater extent than shift area 11. 20 After piston 5 covers passage 12b, the air trapped in advance of the piston is compressed and this pressure is communicated to the opposing holding area 9 through inlet passages 13 and channels 9a. When this 25 pressure balances, or substantially balances, the pressure against holding area 10, the pressure on shift area 11 then preponderates and the valve is thrown to the position shown in Fig. 2. This shifting of the valve takes 30 place about the time that main exhaust 5b is uncovered or begins to be uncovered by piston 5.

As the blow is struck or immediately thereafter, the parts are in the position shown 35 in Fig. 2, the rearward or left end areas 10 and 12, as well as shift area 11, being open to exhaust while motive fluid is now admitted by valve 8 to passage 13 to drive the piston rearwardly. This admitted motive fluid is 40 also effective against area 9, by reason of channels 9a, to hold the valve in its shifted position. As the piston moves rearwardly, it first covers the main exhaust 5b then admits pressure fluid through passage 12b to shift 45 area 12. The valve is not thrown until the air compressed by the piston becomes effective through passage 14 and channels 10a against holding area 10 to put the valve in a state of substantial balance. When the valve shifts, 50 the parts are substantially in the position shown in Fig. 1 and the cycle of operations is complete.

From the above it will be apparent that the valve herein shown is of simple form, 55 wholly imperforate, and arranged to be shifted by air admitted from the piston chamber only when the valve has been placed in a state of balance through the action of air compressed by the piston in its advancing 60 movement, and that such action results from the establishment of communication between the holding areas for the valve and the adjacent ends of the piston chamber.

While the invention has been herein 65 closed in what is now considered to be a pre-

ferred form, it is to be understood that the invention is not limited to the exact details thereof but covers all changes, modifications, and adaptations within the scope of the appended claims. 70

I claim as my invention:

1. A fluid pressure motor comprising a cylinder, a piston reciprocable therein, and a valve for controlling the motive fluid supply to operate said piston and moving automatically in timed relation with the latter, said valve having opposed shift areas, vents for said areas, supply passages thereto under control of said piston, said vents being of less extent than said passages, said valve having opposed holding areas alternately effective to retain the valve in position, means maintaining said holding areas continuously in communication with the opposite ends of said piston chamber, and means alternately subjecting said holding areas to live motive fluid. 80

2. A fluid pressure motor comprising a cylinder, a piston reciprocable therein, and a valve for controlling the motive fluid supply to operate said piston and moving alternately in timed relation with the latter, said valve having opposed shift areas, vents for said areas, supply passages thereto under control of said piston, said vents being of less extent than said passages, said valve having opposed holding areas alternately effective to retain the valve in position, means maintaining said holding areas continuously in communication with the opposite ends of said piston chamber, and means alternately subjecting said holding areas to live motive fluid. 90

3. A fluid pressure percussive tool comprising a casing, providing a piston chamber and a valve chamber, a hammer piston reciprocable within said piston chamber, a valve automatically movable within said valve chamber in timed relation with said piston, said casing having ports and passages extending between said chambers and a main vent port for said piston chamber controlled by said piston, said valve having opposed shift areas, said casing providing supply passages to said areas under control of said piston and continuously open vent ports of smaller extent than said supply passages, said valve having opposed holding areas of greater extent than said shaft areas, and means maintaining said holding areas in communication with the opposite ends of said piston chamber at all times and subject to the fluid pressure conditions obtaining therein. 110

4. A fluid pressure motor comprising a cylinder, a piston reciprocable therein, an imperforate motive fluid controlling valve having a central shifting head, the ends of said valve controlling admission of motive fluid to the cylinder, valve position holding areas intermediate said central head and said 120 125 130

extreme ends, piston controlled means for shifting said valve, and means maintaining communication between said holding areas and the ends of said cylinder.

5 5. A fluid pressure motor comprising a cylinder, a piston reciprocable therein, an imperforate motive fluid controlling valve having a central shifting head, the ends of said valve controlling admission of motive

10 fluid to the cylinder, valve position holding areas intermediate said central head and said extreme ends, said cylinder providing partitions between the holding areas of said valve and the admission chambers at the ends of

15 the latter, said partitions providing communication between said areas and said admission chambers.

6. A fluid pressure motor comprising a cylinder, a piston reciprocable therein, a valve controlling the supply of motive fluid to opposite ends of the cylinder to actuate said piston, said valve having opposed shift areas and opposed holding areas, means controlled by said piston for admitting pressure fluid alternately to said opposed shift areas, and means utilizing air compressed by the piston toward the end of its stroke in one direction against one of said holding areas to assist in the shifting of said valve.

30 7. A fluid pressure motor comprising a cylinder, a piston reciprocable therein, a valve controlling the supply of motive fluid to opposite ends of the cylinder to actuate said piston, said valve having end areas continuously subjected to live motive fluid, said valve also having a central stepped head providing opposed shift areas and opposed holding areas, the holding areas being of greater extent than the shift areas, means controlled

35 by said piston for admitting pressure fluid alternately to said opposed shift areas, and means utilizing air compressed by the piston toward the end of its stroke in both directions for substantially balancing the pressure on

40 said holding areas.

8. A fluid pressure motor comprising a cylinder, a piston reciprocable therein, an imperforate motive fluid controlling valve having a central shifting head, the ends of said valve controlling admission of motive fluid to the cylinder, valve position holding areas intermediate said central head and said extreme ends and of greater extent than the shifting areas on said central head, said cylinder providing partitions between the holding areas of said valve and the admission chambers at the ends of the latter, said partitions providing communication between said holding areas and said admission chambers.

50 9. A fluid pressure motor comprising a cylinder, a piston reciprocable therein, a valve controlling the supply of motive fluid to opposite ends of the cylinder to actuate said piston, said valve having opposed shift areas and opposed holding areas, said hold-

ing areas being of greater extent than said shift areas, means controlled by said piston for admitting pressure fluid alternately to said shift areas, and means utilizing air compressed by the piston at the end of its stroke in one direction against one of said holding areas to assist in the shifting of said valve.

Signed by me at Detroit, in the county of Wayne, and State of Michigan this 15 day of August, 1928.
